T. E. BARTON.
FASTENING DEVICE FOR SCREENS.
APPLICATION FILED JAN. 4, 1913.

1,113,946.

Patented Oct. 20, 1914.

UNITED STATES PATENT OFFICE.

THOMAS E. BARTON, OF WASHINGTON, DISTRICT OF COLUMBIA.

FASTENING DEVICE FOR SCREENS.

1,113,946.

Specification of Letters Patent. Patented Oct. 20, 1914.

Application filed January 4, 1913. Serial No. 740,193.

To all whom it may concern:

Be it known that I, THOMAS E. BARTON, a citizen of the United States, residing at Washington, District of Columbia, have invented certain new and useful Improvements in Fastening Devices for Screens; and I do hereby declare the following to be a full, clear, and exact description of the invention, such as will enable others skilled in the art to which it appertains to make and use the same.

This invention is directed to improvements in securing devices for window screens and has for its object to so construct a device of this character that the same will effectually hold a window screen in the frame.

A further object of the invention is to produce a device of this character so constructed that it may be conveniently attached to a window frame without marring the same.

A still further object of the invention is to provide a device of this character which is exceedingly simple in construction, durable and one which is ornamental in appearance.

With these and other objects in view, this invention resides in the novel features of construction, formation, combinations and arrangements of parts to be hereinafter more fully described, claimed and illustrated in the accompanying drawing, in which:—

Figure 1 is an elevation of a window screen showing it connected to a window frame. Fig. 2 is a sectional view on line 2—2 of Fig. 1.

Referring to the drawing, the numeral 1 designates a window casing, which is of the usual construction and consists of side sills 2 and top and bottom sills 3 and 4, respectively, the side sills being provided near their upper and lower ends with sockets 5, the purpose of which will appear later.

The screen comprises side stiles 6, and upper and lower stiles 7 and 8, respectively, which have their ends secured to the ends of the side stiles. One of the side stiles is provided near its upper and lower ends with bores 9, said bores being so arranged that they register with the sockets 5 formed in the side sills of the window casing. Slidably mounted in the bores 9 are bolts 10, said bolts having their outer ends formed with knobs 11 which when grasped serve to move said bolts into or out of engage-

ment with the sockets 5. Secured to one of the stiles 6 are plates 12, said plates being provided with the right angle flanges 13 which rest flush against the inner edge of the stile so that their inner edges project 60 into the longitudinal recesses 14 formed in the bolts 10, said recesses producing the shoulders 15 and 16, the shoulder 16 limiting the movement of the bolts 10 in one direction and the shoulder 15 the movement 65 in the other direction.

From this construction it will be seen that after the screen is in place and it is desired to remove the same it is only necessary to move the bolts outwardly, whereby 70 the shoulder 16 will engage the right angle flanges 13 so that the outer ends of the bolts will disengage the sockets 5, said shoulders serving to prevent disengagement of the bolts 10 from the stiles 6.

The screen is provided with grips 17 which serve to facilitate the removal or disengagement of the same from the window frame.

A pair of screen doors 18 are hingedly 80 connected to the side stiles of the screen near the lower end so that access may be had to the shutters when desired.

What is claimed is:—

In combination with a window frame having a socket formed in one side sill thereof, of a screen having a bore formed in one of its stiles for registry with the socket of the frame, a bolt slidably engaged in the said bore, a longitudinal recess formed in 90 the bolt and intermediate its ends to produce spaced shoulders, a plate attached to the outer surface of the screen stile and adjacent the bolt, said plate being provided with a right angle flange, the inner end of 95 which engages the recess formed in the bolt, said bolt having its outer end adapted to engage the socket formed in the side sill of the window frame, the sliding movement of said bolt when withdrawn from engagement with the socket being limited upon engagement of one of the shoulders with the right angle flange.

In testimony whereof, I affix my signature, in the presence of two witnesses.

THOMAS E. BARTON.

Witnesses:

SULLIVAN V. JOHNSON,
FRANCIS BOYLE.
